UNITED STATES PATENT OFFICE

JOHN F. O'CONNOR, OF CHICAGO, ILLINOIS, ASSIGNOR TO W. H. MINER, INC., OF CHICAGO, ILLINOIS, A CORPORATION OF DELAWARE

CAR CONSTRUCTION

Application filed January 6, 1930. Serial No. 418,799.

This invention relates to improvements in car construction.

One object of the invention is to provide a combined center and locking pin for body and truck bolsters of railway cars having exceptionally great tensile strength, wherein the pin has head members at opposite ends thereof having shouldered engagement with the bolsters along relatively large areas, the head members being formed by sectional locking blocks embracing enlargements at opposite ends of the pin, one of which is of such a size that it will pass through the pin receiving openings to facilitate application 15 of the pin to the bolsters and locking the same thereto.

A further object of the invention is to provide a combined locking and center pin of the character described in the preceding paragraph, wherein the shank is of smaller diameter than the pin receiving openings of the bolsters, thereby permitting bodily displacement laterally of the pin in assembling the locking blocks therewith, thereby allowing 25 the use of locking blocks having relatively wide retaining shoulders cooperating with the enlargements of the pin and the shoulders of the bolsters.

Other objects of the invention will more 30 clearly appear from the description and claims hereinafter following.

In the drawing, forming a part of this specification, Figure 1 is a top plan view of a portion of a body bolster of a railway car 35 illustrating my improvements in connection therewith. Figure 2 is a vertical, sectional view corresponding substantially to the line 2-2 of Figure 1. Figure 3 is a bottom plan view of the truck bolster illustrated in Figure 2, illustrating my improved pin in connection therewith. And Figure 4 is a detailed, perspective view of a locking block forming a part of the sectional head at one end of the improved center pin.

45 In said drawings, 10 designates the body bolster and 11 the truck bolster of a railway car. The body bolster is provided with a bearing projection 12 cooperating with a bearing seat provided on a block 13 seated in 50 a pocket 14 at the top of the truck bolster.

In carrying out my invention, I provide the body and truck bolsters with aligned center pin receiving openings 15 and 16 of substantially cylindrical cross section and of corresponding diameter. The bearing block 13 is 55 also provided with a pin receiving opening 17 corresponding in cross section and size to the openings 15 and 16 of the body and truck bolsters. The body bolster is provided with a pocket 18 at the outer end of the opening 15, 60 the pocket also being of circular cross section but of larger diameter than the opening 15, thereby providing an annular retaining shoulder 19 at the inner end of said pocket.

The truck bolster is also provided with a 65 pocket 20 which is of circular cross section and is located at the outer end of the pin receiving opening 16 of said bolster. The pocket 20 is of larger diameter than the opening 16, thereby providing an annular 70 retaining shoulder 21 at the inner end of said pocket.

My improved combined locking and center pin comprises broadly a pin member A, a sectional head B at each end of the pin, each 75 head comprising three locking blocks; and a pair of retaining caps C—D cooperating with the sectional heads at opposite ends of the pin.

The pin member A has a shank portion 80 which is of cylindrical cross section and of smaller diameter than the pin receiving openings 15 and 16 of the bolsters, as clearly shown in Figure 2. At the top and bottom ends, the pin member A is provided with enlargements 22—22 which are in the form of annular head members. The enlargements 22—22 are of such a diameter that they will pass through the pin receiving openings of the bolsters, thereby facilitating assembling of 85 the pin with the bolsters. As will be evident, the pin may be assembled with the bolsters by entering the same either through the opening of the body bolster or the opening of the truck bolster, the heads 22 passing freely 90 through the pin receiving openings 15 and 16.

The sectional heads B—B at opposite ends of the pin are of similar construction, except as hereinafter pointed out. Each head preferably comprises three sections 23—23—23, 100

which are in the form of blocks. Each section has a vertical wall portion 24 of cylindrical form, an inner flange 25 laterally projecting therefrom and an outer wall 26. The 5 laterally projecting flange portions 25 of the three blocks 23 together form an annular flange surrounding the shank of the pin inwardly of the corresponding enlargement 22 thereof. The inner end faces of the blocks 10 23 are seated on the annular shoulder of the pocket of the corresponding bolster, as clearly shown in Figure 2. The outer wall portions of the three blocks forming each sectional head B overlie the corresponding end 15 of the pin and together form a complete end wall covering the enlarged portion at that end of the pin. The sections 23 of the head B of the bottom end of the pin differ from the sections 23 at the upper end of the pin in 20 that each section is provided with an upstanding portion 27 at the center thereof, the three upstanding portions 27-27-27 together forming an annular boss for a purpose hereinafter pointed out. The retaining cap C 25 at the upper end of the pin is in the form of a sleeve fitting between the sectional head B at the upper ends of the pin and the side wall of the pocket 18. The sleeve-like member C embraces the three sections of the head 30 B, thereby holding the same locked to the enlargement 22 at that end of the pin. The sleeve C is provided with a bail member 28 by which the same may be manipulated.

The retaining cap D at the bottom end 35 of the pin comprises an annular wall portion 29 which is interposed between the sectional head B at that end of the pin and the side wall of the pocket 20. The bottom wall of the cap D is provided with a central opening 40 30 through which the boss on the sectional head B projects, the opening being surrounded by an upstanding annular flange 31. The projecting boss formed by the portions 27 of the sections 23 of the bottom head B 45 and the annular wall 31 of the cap D are provided with aligned openings adapted to receive a cotter pin 32 by which the cap is secured to the sectional head.

Inasmuch as the shank of the pin member 50 B is of smaller diameter than the corresponding pin receiving openings of the body and truck bolsters, the pin member A is bodily displaceable laterally so as to facilitate assembling of the head members B with the 55 pin. In this connection, it is pointed out that the width of the annular flanges formed by the flange sections 25-25 of the blocks 23 at each end of the pin overlap the annular shoulder formed by the corresponding enlargement 22 and the inner faces of the blocks 23 overlap the annular retaining shoulder of the corresponding bolster to such an extent that the combined overlap of these parts is 60 greater than the clearance between the enlargement 22 and the side wall of the pocket of 65

the corresponding bolster, thereby providing shouldered engagement on relatively wide areas. The employment of locking blocks of this design is made possible by providing the laterally displaceable arrangement of pin member, in that by displacing the pin sufficient clearance is provided between the side of each enlargement and the side wall of the head receiving pocket of the corresponding bolster to permit insertion of the sections of the head. 70

In applying my improved center pin to the bolsters of a railway car for connecting the same, the pin member A is applied by inserting the same either upwardly through the truck bolster or downwardly through the body bolster, the corresponding enlargement 22 being passed through the pin receiving openings of the bolsters. When the pin member A has been positioned as shown in Figure 2, the sectional heads are applied to opposite ends thereof. Each head is applied in the following manner: The pin member A is displaced to one side of the pin receiving openings of the bolsters, thereby providing sufficient clearance between the enlargement 22 and the opposite side wall of the corresponding head receiving pocket to allow passage of the flanged portion at the inner end of one of the blocks 23. This block is then inserted and displaced laterally inwardly to bring the flange 25 thereof beneath the shoulder of the corresponding head 22. The pin is then displaced laterally to permit the successive application of the remaining two 80 blocks of the sectional head in a similar manner, sufficient clearance being provided between the side face of the block 23 first applied, and the corresponding side wall portion of the pocket of the corresponding bolster to permit the necessary displacement of the pin member A to allow insertion of the section 23 at the other side of the pin. 85

After the two sectional heads B-B have been applied the retaining members C and D are telescoped over the head members B and the retaining cap D is secured to the lower sectional head B by the cotter pin 32. 90

In separating the bolster, the pin is removed by a procedure substantially the reverse of the assembling operation, the two caps C and D being first removed from the sectional heads and the pin member B then laterally displaced in proper directions to allow disengagement of the three sections 23 successively from the corresponding enlargement of the pin member A. When the sectional members B-B have been completely removed from the enlargements of the pin, the pin member A may be either withdrawn by lifting the same upwardly through the body bolster, or by permitting the same to drop through the truck bolster. 95

I have herein shown and described what I now consider the preferred manner of carry- 100

ing out my invention, but the same is merely illustrative and I contemplate all changes and modifications that come within the scope of the claims appended hereto.

5 I claim:

1. In car construction, the combination with body and truck bolsters having alined center pin receiving openings, each bolster having a head receiving pocket adjacent its opening, said pocket being of larger diameter than the corresponding opening, thereby providing an annular retaining shoulder at the inner end of the pocket; of a center pin member having a shank of smaller diameter than said center pin openings, said pin having cylindrical enlargements at opposite ends thereof, of not greater diameter than said pin receiving openings but of smaller diameter than said pockets, thereby providing annular retaining shoulders at opposite ends of said shank; and a plurality of locking blocks at each end of the pin providing sectional head members embracing the corresponding enlargements and each having an inwardly projecting annular sectional flange of a width corresponding to that of the annular shoulder of the corresponding enlargement, each set of blocks together defining a sectional head member of smaller diameter than the corresponding pocket and overlapping the annular retaining shoulder thereof, the combined width of said inwardly projecting flange and the overlap of said head with the retaining shoulder of the corresponding pocket being greater than the clearance between said head of the side wall of said pocket, said pin member being laterally displaceable in said pin receiving openings to permit insertion of the parts of the sectional heads within said head receiving pockets between the side walls of said pockets and the enlargements of the pin member.
2. In car construction, the combination with body and truck bolsters having alined center pin receiving openings, each bolster having a head receiving pocket at the outer end of its opening, said pocket being of greater cross sectional size than the pin receiving opening, thereby providing a retaining shoulder at the inner end of said pocket; of a center pin member having a shank portion of smaller cross section than said pin receiving openings, said pin member having enlargements at opposite ends thereof, each enlargement being of a cross section not greater than said pin receiving openings; a plurality of locking blocks embracing each of said enlargements and having shouldered engagement therewith and with the retaining shoulders of the corresponding bolsters, the combined overlap of said shouldered engagement of the blocks and said enlargement and retaining shoulder at each end of the pin being greater than the clearance between said enlargement and the side wall of

the pocket of the corresponding bolster; and a retaining member having a sleeve portion embracing said blocks and occupying the space between the same and the side wall of the corresponding pocket.

3. In car construction, the combination with body and truck bolsters having alined center pin receiving openings, each bolster having a retaining shoulder at the outer end of its opening; of a center pin member extending through said openings and having enlargements at opposite ends thereof, one of said enlargements being of such a size as to pass through said openings; a sectional head embracing said last named enlargement and having shouldered engagement with the shoulder of the corresponding bolster, said sectional head comprising three locking block members arranged in annular series and having inwardly extending flange portions providing the shouldered engagement with said enlargement; and detachable means for maintaining said sectional head interlocked with said enlargement.

4. In car construction, the combination with body and truck bolsters having alined center pin reeciving openings, each bolster having a recess adjacent the outer end of its opening, said recess being of greater width than said opening, thereby providing a retaining shoulder; of a center pin member having a shank of smaller diameter than the openings, thereby providing clearance therebetween to allow lateral displacement of said shank, said pin member having enlargements at opposite ends thereof adapted to be accommodated in said recesses, at least one of said enlargements being of such a size as to pass through said openings; and locking blocks embracing said last named enlargement and having shouldered engagement therewith and with the shoulder of the corresponding bolster, the clearance between said blocks and the outer wall of the recess being less than the overlap provided by said shouldered engagement, each of said blocks and said pin being laterally displaceable in reverse directions to an extent to effect disengagement of the blocks from the enlargement of the pin.

5. In car construction, the combination with body and truck bolsters having alined center pin receiving openings, each bolster having a pocket adjacent the outer end of its opening, said pocket being of greater width than the opening, thereby providing a retaining shoulder; of a center pin member having a shank portion disposed in said pin receiving openings, said pin member having enlargements at opposite ends thereof, each enlargement being of a cross section not greater than said pin receiving openings; and a plurality of locking blocks embracing each of said enlargements and having shouldered engagement therewith and with the retaining shoulders of the corresponding bolsters, said

blocks being laterally outwardly displaceable in said pocket to an extent less than the shouldered overlap of the blocks and enlargement, and said shank portion of the pin being of smaller size than the pin receiving openings, whereby said pin is bodily displaceable laterally in said openings to an extent to effect complete disengagement of the blocks and enlargement when said shank and blocks are displaced laterally in reverse directions.

10 6. In car construction, the combination with body and truck bolsters having aligned center pin receiving openings, each bolster having a head receiving pocket at the outer end of its opening, said pocket being of greater diameter than the opening, thereby providing an annular retaining shoulder at the inner end of said pocket; of a center pin member having a shank of smaller diameter than the openings, said pin member having enlargements at opposite ends thereof, at least one of said enlargements being of such a size as to pass through said openings; and a detachable cylindrical head including a plurality of locking blocks embracing said last named enlargement and having shouldered engagement therewith and with the shoulder of the corresponding bolster, said head being of smaller size than the corresponding pocket, the clearance between the side walls of said pocket and head being less than the shouldered overlap of each block and enlargement, said shank of the pin being laterally displaceable from centered position in said pin receiving openings to an extent at least as great as the difference between the clearance between the head and the side walls of the pocket and the overlap of said shouldered engagement.

40 7. In car construction, the combination with body and truck bolsters having aligned center pin receiving openings, each bolster having a head receiving pocket at the outer end of its opening, said pocket being of greater cross sectional size than the pin receiving opening, thereby providing a retaining shoulder at the inner end of said pocket; of a center pin member having enlargements at opposite ends thereof, one of said enlargements being of a cross section not greater than said pin receiving openings and being disposed in the corresponding pocket; and a plurality of locking blocks disposed in said pocket, embracing said last named enlargement and having shouldered engagement therewith and with the retaining shoulder of the corresponding bolster, said blocks being outwardly displaceable in said pocket to an extent less than the shouldered overlap of the blocks and enlargement, the shank of said pin being of smaller cross sectional size than the pin receiving openings, the clearance between said shank and the walls of said opening being such that the pin is laterally displaceable to an extent to permit disengagement of

each block from said enlargement when said block is moved laterally outwardly in the pocket to the extent of the clearance provided between the block and the wall of said pocket.

70 In witness that I claim the foregoing I have hereunto subscribed my name this 3rd day of January, 1930.

JOHN F. O'CONNOR.
